(57) **CLAIM**

The ornamental design for a housing for an electronic device with a display screen, as shown and described.

DESCRIPTION

FIG. 1 is a perspective rear view of a housing for an electronic device with a display screen.

FIG. 2 is a left-side view of the housing for an electronic device with a display screen of FIG. 1.

FIG. 3 is a right-side view of the housing for an electronic device with a display screen of FIG. 1.

FIG. 4 is a front view of the housing for an electronic device with a display screen of FIG. 1.

FIG. 5 is a rear view of the housing for an electronic device with a display screen of FIG. 1.

FIG. 6 is a top view of the housing for an electronic device with a display screen of FIG. 1; and,

FIG. 7 is a bottom view of the housing for an electronic device with a display screen of FIG. 1.

The broken lines shown represent the portions of the housing for an electronic device with display screen that form no part of the claimed design.

1 Claim, 7 Drawing Sheets
